(57) **CLAIM**

I claim the ornamental design for a convertible fitted/flat bed sheet, as shown and described.

DESCRIPTION

FIG. 1 is a bottom front perspective view of a convertible bed sheet, showing my new design in a fitted-sheet configuration; FIG. 2 is an enlarged bottom front perspective view thereof; FIG. 3 is a top front perspective view thereof, illustrated in a flat-sheet configuration;

FIG. 4 is an enlarged bottom front perspective view of FIG. 3;

FIG. 5 is an enlarged top plan view of FIG. 3;

FIG. 6 is an enlarged bottom plan view of FIG. 4;

FIG. 7 is a front elevational view of FIG. 5, the left-side elevational view being a mirror image thereof; and,

FIG. 8 is a rear elevational view of FIG. 5, the right-side elevational view being a mirror image thereof.

The broken lines showing additional portions of the convertible bed sheet in the drawings form no part of the claimed design.
